CIGARETTE ROLLING DEVICE

Lionel Guy Moss, Dunbar, W. Va.

Application March 13, 1945, Serial No. 582,510

5 Claims. (Cl. 131—51)

1

This invention concerns a simple, cheap and easily operated device for rolling cigarettes; and which by its compactness and lack of protruding parts can be carried in the pocket or stored in a drawer.

An illustrative form of construction is shown on the accompanying drawings, in which:

Figure 1 is a perspective view of the device with the parts in position to be charged.

Figures 2 to 5 are longitudinal sectional views showing the successive positions occupied during charging and rolling.

Figure 6 is a cross-section substantially on line 6—6 of Fig. 4.

The structure is illustrated as consisting of three relatively movable parts, which are a base 10; a slider 11, and a flexible apron 12.

The base 10 has upstanding side walls 15 with inwardly projecting upper guide ribs 16 for a part of the length from the discharge end, these ribs 16 being omitted above the charging point. The spacing of these side walls corresponds to the desired length of the cigarette. The floor portion 17 of the base is provided with a cross-groove 18 at which charging is effected, and whose size serves to measure the amount of tobacco for the cigarette. The floor and side walls provide a trough-like structure which is open at both ends. A dowel 19 extends upwardly from the floor.

The slider 11 is longer than the base and has a rounded nose at its advancing end (toward the left in Figs. 2 to 5), with a large-radius arc 21 smoothly merging with the plane top of the slider, and having at the extreme end of the slider a lesser radius arc 22 which ends essentially in the plane of the bottom of the body of the slider. Behind the nose, a cross-groove 23 is formed by curved wall surfaces which provide a pocket to receive the tobacco during rolling, the rearward wall having its junction with the plane bottom of the slider at a dihedral angle 24 less than 90 degrees. This groove 23 has a smoothly curved wall which for a major part is a circular semi-cylinder of a size closely corresponding to the desired diameter of the cigarette. The bottom of the slider has a longitudinal groove 25 cooperative with the dowel 19 for limiting the movement of the slider.

The apron 12 is flexible, and preferably is of rubberized cloth, which does not cling tightly to particles of the tobacco, and has resistance against elastic stretching. In the illustrated form, the apron has hems at each end; one hem being looped around the cross pin 27 which is seated in the side walls 15 near the rear end of the base, 55

2

the other hem being fastened to the front of the base. The width of the apron closely conforms to the spacing between the side walls 15 so that it can lie flat on the floor portion 17; while its length permits it to be tucked into the charging groove 18 and also to form a slack loop between the groove and the pin 27 (see Figs. 1 and 2).

In operation, the slider 11 is withdrawn to the position of Figs. 1 and 2. The apron 12 is tucked 10 into the cross-groove 18, as shown in these figures, with its slack rearward of the groove. Tobacco T is then loaded into the pocket formed by the belt, as shown in Fig. 2, with the size of the groove 18 serving to measure the quantity; and a paper P 15 is placed flat upon the apron at a point between the groove 18 and the front or discharge end of the floor 17, with the gummed edge G moistened and located remote from the groove 18.

The slider 11 is now pushed inward (toward 20 the left in Figs. 2 to 5). The rounded nose causes the material of the slack loop of the apron to be pushed over the tobacco T lying in the pocket and, as the slider movement continued, the apron bight between the base and the slider and in the groove 25 18, with its charge of tobacco, is transferred into the cross-groove of the slider 11 (Fig. 3). As the slider moves, the apron passes around the rounded nose after travelling around the curved walls of the slider cross-groove and causes the tobacco T 30 to be rolled over and over and compacted into cylindrical form. The progress of the rolling tobacco T brings it onto the paper P, and the apron guides the paper around the tobacco (Fig. 4) until the advancing edge is brought against the paper still flat on the floor 17 and then the other surface of this wrapping paper is contacted 35 with the moistened adhesive, and the rolling continued. It will be noted that the slider may be left at rest, after the paper has "disappeared" into the cross-groove in the slider, to assure sticking and setting of the adhesive, if desired.

The final movement of the slider 11 brings its nose beyond the floor 17 (Fig. 5), and the taking up of slack in the apron 12 causes ejection of the finished cigarette X.

The device is now ready to form a new cigarette by withdrawing the slider 11, and proceeding as before.

During the early part of its movement, the slider is held between the floor 17 and the portion of the apron looped about the pin 27, and can be rocked about a traverse axis (dotted line 50 positions of apron and slider, Figs. 1 and 2) and back during the initial inward sliding movement, 55 to start the forming; and the apron has a length

coordinated with the length of the ribs 15, so that the slider 11 must enter below these ribs essentially at the time the tobacco T is being transferred from the groove 18 into the groove 23. The slider and belt have a total looseness of about one-sixteenth of an inch in the space between the floor 11 and the guide ribs 16, during the rolling and assembling positions of the operation, which permits the sliding movement but also produces pressure upon the tobacco cylinder which is being formed.

The base 10 may be made of a single piece of wood, plastic, etc., or can be of several pieces secured fixedly together, as indicated in Fig. 6.

The pin 27 is illustrated as of uniform diameter from end to end and having a force-fit in the holes in the side walls 15; so that by forcing the pin 27 endwise, it can be inserted in and removed from the base for assembly and disassembly of the device. Such dowel pivot pin assemblies are well-known as, for example, in the Pollak Patent No. 194,928 and the Ligon Patent No. 1,925,640.

When it is desired to include a filter in the cigarette, the filter plug F (Fig. 1) may be laid in the tobacco pocket during charging; and then it also is rolled and wrapped by the paper during the operation.

The employment of the two cross grooves 18 and 23 permits accurate formation of cigarettes of uniform size and having a tightness of compacting as desired by the user. The groove 18, with the apron therein, permits the measuring of the desired amount of tobacco, the maximum amount being indicated by filling of the groove. By compacting the tobacco in the groove, a "tighter" fill or harder cigarette is produced. The transfer of the travelling bight of the apron, with its charge of tobacco, into the close-embracing cross groove 23, causes the rolling and compressing of the mass preliminary to and during the operation of wrapping it; and this compressing is a function of the hard and shape-maintaining walls of this groove rather than of the flexible but essentially non-extensible belt itself, so that the cigarettes having an essentially predetermined diameter regardless of the amount of the charge. The device is capable of rolling various kinds of tobacco such as shredded, crimp-cut, broken leaf, etc.

It is obvious that the illustrated form may be modified within the scope of the appended claims.

What is claimed:

1. A cigarette roller having a base with a cross groove therein, a slider movable along the base and having a cross-groove which is aligned with the base cross-groove during an early part of such relative movement, and a flexible, essentially non-extensible apron fastened at its ends to the base and having a length greater than the distance between the ends of the base effective to form a bight between the base and slider and

engaging the wall of the slider cross-groove during the relative movement.

2. A cigarette roller comprising a base having a cross-groove therein to provide a tobacco-measuring pocket, a slider movable along the base and having a cross-groove spaced from the front end thereof, and a flexible, essentially non-extensible apron fastened at its ends to said base, the slider being movable along said base beneath the apron and in its rearmost position exposing the base groove whereby the apron may be tucked into the base groove for receiving the tobacco, said apron having longitudinal slack for positioning rearward of the base groove to permit an initial movement of the slider past the base groove until the grooves are aligned, the slider groove having a size and form for receiving a bight of the apron and the tobacco and causing rolling thereof as the slider advances and for rolling around the tobacco a wrapping paper originally positioned on the apron between the base groove and the discharger end of the base.

3. A cigarette roller comprising a trough-like base having inwardly extending guide ribs on its side walls, a slider movable along and closely fitting the walls of the base, the floor of the base having a cross-groove therein, said slider having a rounded nose and a cross-groove in its lower surface adjacent said nose, and a flexible, essentially non-extensible apron fastened at its ends to the base and fitting therein for conforming to the said base floor and the cross-groove thereof during charging, said slider being guided and confined by the base floor and the guide ribs during its final sliding forward movement.

4. A cigarette roller having a base with a cross-groove therein, a slider movable along the base and having a cross-groove which is aligned with the base cross-groove during an early part of such relative movement, and a flexible, essentially non-extensible apron fastened at its ends to the base and having a length greater than the distance between the ends of the base effective to form a bight between the base and slider and engaging the wall of the slider cross-groove during the relative movement; said slider having a rounded nose at its front edges for facilitating the sliding of said apron therearound during the relative movement, said slider cross-groove having the major portion of its wall of circular semi-cylindrical shape for guiding a part of the apron bight while acting through the apron for compressing a charge of tobacco in said bight.

5. A cigarette roller as in claim 1, in which the slider has a plane bottom for movement along a plane surface of the base, and the slider cross groove has the edge of the rearward part of its wall joining the slider bottom at a dihedral angle less than 90 degrees.
